CLAIM

I claim the ornamental design for an automobile wheel, as shown and described.

DESCRIPTION

FIG. 1 is a front view of an automobile wheel, showing my new design;

FIG. 2 is a perspective view thereof;

FIG. 3 is a front view of a second embodiment of an automobile wheel, showing my new design;

FIG. 4 is a perspective view thereof;

FIG. 5 is a front view of a third embodiment of an automobile wheel, showing my new design;

FIG. 6 is a perspective view thereof;

FIG. 7 is a front view of a fourth embodiment of an automobile wheel, showing my new design; and,

FIG. 8 is a perspective view thereof.

In the drawings, the broken lines depict environmental subject matter only and form no part of the claimed design.
